SHEET METAL FASTENER

Joseph W. Drion, 2627 Melvin, Brentwood, Mo.

Filed Mar. 10, 1959, Ser. No. 54,916

Term of patent 14 years

(Cl. D54—10)

FIG. 1.

FIG. 4.

FIG. 2.

FIG. 5.

FIG. 3.

FIG. 6.

FIGURE 1 is a top plan view of the sheet metal fastener showing my new design,

FIGURE 2 is a front elevation of the same,

FIGURE 3 is a bottom plan view of the sheet metal fastener,

FIGURE 4 is a rear elevation of the same, and

FIGURE 5 is side elevation of the sheet metal fastener, the other side not shown is a mirror image thereof.

FIGURE 6 is a perspective view taken from the front left of FIG. 4.

I claim:

The ornamental design for a sheet metal fastener, as shown.
